corporation of Virginia

Filed June 6, 1962, Ser. No. 70,437

Term of patent 14 years

(Cl. D74—1)

FIG. 1

FIG. 2

FIG. 3

FIG. 4

FIG. 5

FIGURE 1 is a top plan view of a telephone index, showing my new design;

FIGURE 2 is a front perspective view thereof;

FIGURE 3 is a side elevational view thereof;

FIGURE 4 is a front perspective view thereof as it appears in open position with one of the keys depressed; and

FIGURE 5 is a rear elevational view thereof.

The dominant feature of my design resides in the solid lines of the drawings showing the recessed key panel with upright triangular keys in combination with the rectangular cover and base, all as shown.

I claim:

The ornamental design for a telephone index, as shown and described.
